**FLOATING ROOF ANTI-ROTATIONAL
MECHANISMS**
John H. Wiggins, 801 C El Camino Real,
Menlo Park, Calif.
Filed Nov. 1, 1962, Ser. No. 234,805
20 Claims. (Cl. 220—26)

The present invention relates to storage tanks for liquids, particularly petroleum products, or the like, and provided with floating roofs, and more particularly to anti-rotational mechanisms for the floating roofs in the storage tanks.

A storage tank of the type mentioned conventionally comprises an upstanding substantially cylindrical side wall provided with an open top; and a substantially disk-shaped piston-like floating roof is arranged in the tank in floating relation with the stored liquid and movable in the vertical direction with respect to the side wall in accordance with the head of the stored liquid. The floating roof is positioned radially inwardly with respect to the side wall to provide a substantially annular space therebetween; and substantially annular sealing structure is carried by the periphery of the floating roof and arranged in the annular space and disposed in sliding sealed engagement with the side wall. Thus, the floating roof is subject to rotation in a generally horizontal plane with respect to the side wall, particularly when the floating roof is subjected to a wind or rain storm; and of course, such rotation of the floating roof through any substantially angle with respect to its normal position in the tank is highly objectionable and may cause substantial damage to various appliances and fixtures carried by the floating roof.

While a number of mechanisms have been proposed heretofore to prevent or to limit such rotation of the floating roof with respect to the tank, none of these mechanisms has been entirely satisfactory in operation and all of these mechanisms have been altogether too expensive.

Accordingly, it is a general object of the present invention to provide an anti-rotational mechanism for a floating roof that is both entirely satisfactory in operation and economical to manufacture and to maintain in service.

Another object of the invention is to provide a mechanism for controlling and limiting the rotation of a floating roof with respect to its normal rotary centered position within the side wall of the associated storage tank that essentially comprises a strong flexible resilient cable arranged in the tank and secured in taut condition between upper and lower anchor structures rigidly secured to the side wall of the tank respectively adjacent to the top and to the bottom thereof, wherein the cable is normally disposed in a substantially vertical position extending through a cooperating upstanding opening provided in the peripheral portion of the floating roof when the floating roof occupies its normal rotary centered position, whereby undesirable rotation of the floating roof in either direction out of its normal rotary centered position effects corresponding deflection of the intermediate section of the cable passing through the upstanding opening mentioned from its substantially vertical position, so that the thus deflected cable exerts a force upon the floating roof that is productive of a torque thereupon tending to restore the floating roof back into its normal rotary centered position.

Another object of the invention is to provide a mechanism of the character described that also comprises a cable guiding device carried by the floating roof adjacent to the upstanding opening therein and cooperating with the adjacent intermediate section of the cable.

Another object of the invention is to provide a mechanism of the character described, wherein the incorporated cable guiding device is operative to resolve an undesirable

2

rotary movement of the floating roof in either direction out of its normal rotary centered position into corresponding circumferential and radial components.

5 A further object of the invention is to provide a mechanism of the character described that further comprises a seal arranged to prevent the escape of vapors from the stored liquid through the upstanding opening in the floating roof.

10 A further object of the invention is to provide a mechanism of the character described that further comprises a seal arranged to prevent the entry of rain and the other elements of weather into the incorporated cable guiding device.

15 Further features of the invention pertain to the particular arrangement of the elements of the anti-rotational mechanism for the floating roof, whereby the above-outlined and additional operating features thereof are attained.

20 The invention, both as to its organization and method of operation, together with further objects and advantages thereof, will be understood by reference to the following specification, taken in connection with the accompanying drawings, in which:

25 FIGURE 1 is a top perspective view, partly broken away, of a tank for storing liquids, such as petroleum products, and provided with a floating roof and incorporating an anti-rotational mechanism for the floating roof embodying the present invention;

30 FIG. 2 is an enlarged top perspective view of fragmentary portions of the storage tank, the floating roof and a sealing mechanism carried by the floating roof and arranged in sliding sealed engagement with the side wall of the storage tank;

35 FIG. 3 is an enlarged top perspective view, partly broken away, of the anti-rotational mechanism;

40 FIG. 4 is a further enlarged vertical sectional view of a tensioning device incorporated in the anti-rotational mechanism, as shown in FIG. 3;

45 FIG. 5 is a further enlarged horizontal sectional view of the tensioning device, this view being taken in the direction of the arrows along the line 5—5 in FIG. 4;

50 FIG. 6 is a further enlarged horizontal sectional view of the tensioning device, this view being taken in the direction of the arrows along the line 6—6 in FIG. 4;

55 FIG. 7 is a diagrammatic view of the mode of resolving forces exerted upon the floating roof into corresponding radial and circumferential components;

60 FIG. 8 is a further enlarged plan view, partly broken away, of a modified form of a cable guiding device that may be incorporated in the anti-rotational mechanism, as shown in FIG. 3;

65 FIG. 9 is a further enlarged vertical sectional view of the cable guiding device, this view being taken in the direction of the arrows along the radially extending line 9—9 in FIG. 8;

70 FIG. 10 is a further enlarged vertical sectional view of the cable guiding device, this view being taken in the direction of the arrows along the circumferentially extending line 10—10 in FIG. 9;

75 FIG. 11 is a further enlarged plan view, partly broken away, of another modified form of a cable guiding device that may be incorporated in the anti-rotational mechanism, as shown in FIG. 3; and

80 FIG. 12 is a further enlarged vertical sectional view of the cable guiding device, this view being taken in the direction of the arrows along the radially extending line 12—12 in FIG. 11.

85 Referring now to FIGS. 1 to 3, inclusive, of the drawings, there is illustrated a tank 10 for storing liquids, such as petroleum products, that comprises an upstanding substantially cylindrical side wall 11 and a substantially disk-shaped bottom wall 12 and provided with an

open top. The top of the side wall 11 terminates in an annular radially outwardly directed curb 13; and an annular radially outwardly directed wind girder 14 is carried by the upper portion of the side wall 11 and arranged below the curb 13. The wind girder 14 projects radially outwardly well beyond the curb 13 and is supported by a plurality of circumferentially spaced-apart gusset plates 15 arranged between the bottom of the wind girder 14 and the adjacent upper portion of the side wall 11. The outer periphery of the wind girder 14 terminates in a formed rim 16 that extends first upwardly and then radially inwardly and ultimately downwardly.

Arranged within the storage tank 10 is a floating roof 20 that essentially comprises a substantially disk-shaped hollow central pontoon 21, a substantially annular hollow outer pontoon 22, and a substantially annular deck sheet 23 joining the pontoons 21 and 22. More particularly, the outer pontoon 22 comprises an outer rim 24, an inner rim 25, a top plate 26 joining the top portions of the rims 24 and 25, and a bottom plate 27 joining the bottom portions of the rims 24 and 25. The outer rim 24 of the outer pontoon 22 is substantially cylindrical and is disposed in upstanding position and spaced radially inwardly with respect to the side wall 11 of the storage tank 10, so as to provide an annular space 28 therebetween.

An annular sealing mechanism 30 is carried by the outer rim 24 of the outer pontoon 22 and arranged in the annular space 28 and disposed in sliding sealed engagement with the side wall 11 of the storage tank 10. The sealing mechanism 30 may be of any suitable type, such, for example, as that disclosed in U.S. Patent No. 3,043,468, granted on July 10, 1962, to Frank W. Horner, Jr.

An annular weather hood 40 is carried by the top of outer rim 24 of the outer pontoon 22 and is directed upwardly and radially outwardly over the top of the annular space 28 and positioned above the sealing mechanism 30 and cooperates in sliding engagement with the side wall 11 of the storage tank 10. The weather hood may be of any suitable type, such, for example, as that disclosed in U.S. Patent No. 2,997,200, granted on August 22, 1961, to Anthony P. Giannini and Eli F. Smith.

Further, the storage tank 10 comprises an anti-rotational mechanism 50 for the floating roof 20; which mechanism 50 embodies the features of the present invention. More particularly, as shown in FIGS. 1 and 3, the anti-rotational mechanism 50 comprises upper anchor structure 60 arranged at the top of the tank 10, and lower anchor 70 arranged in the tank 10 adjacent to and above the bottom wall 12 thereof. The upper anchor structure 60 includes a substantially horizontally disposed beam 61, the intermediate portion of which is rigidly secured to the top of a short upstanding column 62. The bottom of the column 62 is rigidly secured to a plate 63, that is, in turn, rigidly secured to the curb 13. The outer end of the beam 61 projects radially outwardly over the wind girder 14; and the extreme outer end of the beam 61 is rigidly secured to the wind girder 14 by a tie bar 64 extending therebetween. Specifically, the upper end of the tie bar 64 is rigidly secured to the extreme outer end of the beam 61 and the lower end of the tie bar 64 is rigidly secured to the rim 16 of the wind girder 14. The inner end of the beam 61 projects generally radially inwardly into overhanging relation with the outer peripheral portion of the outer pontoon 22. The lower anchor structure 70 includes a substantially horizontally disposed beam 71; the outer end of the beam 71 is rigidly secured to the side wall 11; and the outer end of the beam 71 projects generally radially inwardly into underhanging relation with the outer peripheral portion of the outer pontoon 22. Also the outer end portion and the intermediate portion of the beam 71 are rigidly braced to the side wall 11 against undesirable upward bending relative to the side wall 11 by a number of structural elements

72, 73 and 74. Specifically, the plate 72 is rigidly secured mutually to the outer end of the beam 71 and to the adjacent portion of the side wall 11; the angle 74 is rigidly secured to the side wall 11 at a position disposed above the plate 72; and the strut 73 is disposed in an upwardly and radially outwardly directed position between the intermediate portion of the beam 71 and the angle 74, the lower end of the strut 73 being rigidly secured to the intermediate portion of the beam 71 and the upper end of the strut 73 being rigidly secured mutually to the side wall 11 and to the angle 74.

In the mechanism 50, the upper and lower beams 61 and 71 are disposed in vertical alignment with each other; the extreme inner end of the upper beam 61 carries a tensioning device 80 rigidly secured thereto; the outer end of the lower beam 71 carries an upwardly directed lug 75 rigidly secured thereto; and the tensioning device 80 and the lug 75 are disposed in vertical alignment with each other for a purpose more fully explained hereinafter.

Referring now to FIGS. 4, 5 and 6, the tensioning device 80 essentially comprises an upstanding substantially cylindrical casing 81 including a tubular side wall 82, a bottom wall 83 rigidly secured in the bottom end of the side wall 82, and a top wall 84 removably secured in the top of the side wall 82, the upper portion of the side wall 82 being rigidly secured to the extreme outer end of the upper beam 61. An upper piston 85 is mounted in the upper portion of the side wall 82 for vertical adjusting movements, the central portion of the piston 85 carrying an upwardly directed rod 86 rigidly secured thereto. Two radially outwardly directed and diametrically disposed lugs 87 are carried by the piston 85 and arranged in two upstanding parallel guide slots 82a formed in the inner wall of the side wall 82, thereby to prevent rotation of the piston 85 with respect to the side wall 82. The upper end of the rod 86 is threaded, as indicated at 86a, and projects to the exterior of the casing 81 through a centrally disposed hole provided in the top wall 84; which threaded upper end of the rod 86 carries an adjusting nut 88 and a lock nut 89 both disposed above the top wall 84. A lower piston 90 is mounted in the lower portion of the side wall 82 for vertical adjusting movements; and the two pistons 85 and 90 are rigidly connected together by a pair of oppositely disposed vertically extending straps 91. Thus, the vertical position of the piston 85 may be selectively adjusted by appropriate adjustment of the nut 88 on the rod 86; and this adjustment may be preserved by setting the lock nut 89. As the vertical position of the piston 85 is adjusted, the vertical position of the piston 90 is likewise adjusted through the straps 91 rigidly connected between the pistons 85 and 90. An intermediate piston 92 is mounted in the intermediate portion of the side wall 82 for vertical movements independently of the pistons 85 and 90; and a pair of oppositely disposed notches 92a are formed in the sides of the piston 92 to receive the straps 91, so as to prevent rotation of the piston 92 relative to the side wall 82. An upstanding rod 93 passes through aligned holes respectively provided in the central portions of the bottom wall 83 and the two pistons 90 and 92; and the extreme upper end of the rod 93 carries an enlarged head 94 engaging the top surface of the piston 92. A resilient helical compression spring 95 is arranged in surrounding relation with the upper portion of the rod 93 and interposed with respect to the pistons 90 and 92.

In the tensioning device 80, when the rod 93 is moved downwardly, the piston 92 moves downwardly therewith, whereby the spring 95 is compressed between the pistons 92 and 90, thus resiliently opposing the downward movement of the rod 93. Also, the compression of the spring 95 tends to cause the restoration of the piston 92, and consequently the rod 93, back upwardly into its initial position. Furthermore, the initial vertical position of the piston 90, and consequently the initial compression of the

spring 95, may be selectively adjusted by manipulation of the nuts 88 and 89, as previously explained.

Again referring to FIG. 3, an upstanding tube 96 is arranged between the upper and lower sheets 26 and 27 in the outer peripheral portion of the outer pontoon 22, the upper and lower ends of the tube 96 being suitably hermetically sealed in place in corresponding openings respectively provided in the sheets 26 and 27. The floating roof 20 has a normal rotary centered position with respect to the side wall 11 of the storage tank 10, as explained more fully hereinafter, wherein the upstanding passage provided through the tube 96 is arranged in vertical alignment with respect to the tension device 80 carried on the inner end of the upper beam 61 and the lug 75 carried on the inner end of the lower beam 71.

Further, the mechanism 50 comprises a strong flexible resilient cable 97 operatively connected between the lug 75 and the tension device 80 and extending through the upstanding passage provided in the tube 96; which cable 97 is preferably of the twisted strand type and formed essentially of stainless steel, thereby to obtain the quality of corrosion resistance, together with strength, flexibility and resiliency, as noted above. Specifically, the lower end of the rod 93 carried by the tension device 80 terminates in a clevis 98 rotatably secured thereto; and the upper end of the cable 97 is looped through the clevis 98 and firmly secured upon itself by cable clamps 99; and the lower end of the cable 97 is looped through a hole provided in the lug 75 and firmly secured upon itself by cable clamps 100. In the arrangement the cable 97 is maintained in taut condition between the clevis 98 and the lug 75 by the tension device 80; and the initial tension in the cable 97 is preset, as desired, by adjustment of the nuts 88 and 89 with respect to the rod 86, in the manner previously explained. When the floating roof 20 occupies its normal rotary centered position with respect to the side wall 11 of the tank 10, the cable 97 is disposed in a substantially vertical position passing through the tube 96 and out of contact therewith by virtue of the previously mentioned vertical alignment of the upstanding opening in the tube 96 with the clevis 98 and the lug 75 and the initial tension in the cable 97 is established and maintained by the tension device 80. In passing it is mentioned that to the inherent resiliency of the cable 97, the resiliency of the compression spring 95 incorporated in the tension device 80 is added, in the overall mounting arrangement of the cable 97 between the clevis 98 and the lug 75.

Further, the mechanism 50 comprises a cable guiding device 110 carried by the outer pontoon 22 of the floating roof 20 and cooperating with the intermediate section of the cable 97 just above the top of the tube 96. Specifically, the cable guiding device 110 comprises a pair of upstanding plates 111 rigidly secured to the top surface of the top plate 26 of the outer pontoon 22; which plates 111 extend in the circumferential direction of the floating roof 20 and are spaced-apart in the radial direction of the floating roof 20. A pair of elongated spindles 112 are carried by the plates 111; which spindles 112 extend radially and are disposed in circumferential spaced-apart relation with respect to the floating roof 20, the spindles 112 being respectively arranged on opposite sides of the adjacent intermediate section of the cable 97. A pair of elongated rollers 113 are respectively rotatably mounted upon the spindles 112 and respectively engage the opposite sides of the adjacent intermediate section of the cable 97. Thus, the cable 97 passes through the cable guiding device 110, and thence through the tube 96, the cable being boxed or framed by the pair of plates 111 and the pair of rollers 113. Thus, it will be understood that as the floating roof 20 rises and falls in accordance with the head of the stored liquid and with respect to the side wall 11 of the tank 10, the cable 97 is fed through the cable guiding device 110 in the required direction, and without the exertion of any particular force between the cable 97 and the cable guiding device 110, as long as the floating roof 20

20 occupies its normal rotary centered position with respect to the side wall 11.

Referring now to FIG. 7, there is diagrammatically shown the floating roof 20, the sealing mechanism 30 carried by the outer rim 24 of the outer pontoon 22 thereof, the side wall 11 of the storage tank 10, the cable 97 and the cable guiding device 110; wherein the floating roof 20 occupies its normal rotary centered position with respect to the side wall 11, with the result that the sealing mechanism 30 is substantially uniformly compressed radially about the circumference thereof between the floating roof 20 and the side wall 11. Now, the wind may exert a force upon the floating roof 20 from any direction whatsoever, tending to move the same from its normal centered position, tending to rotate the same about its own center, etc. For purposes of explanation, it is convenient to consider the major horizontal axis of the floating roof 20 as being oriented W-E and passing through the cable 97 in its vertical position. A force SW exerted upon the floating roof 20 may be resolved into a horizontal component W1 and a vertical component S1; a force NW exerted upon the floating roof 20 may be resolved into a horizontal component W2 and a vertical component N2; a NE force exerted upon the floating roof 20 may be resolved into a horizontal component E3 and a vertical component N3; and a SE force exerted upon the floating roof 20 may be resolved into a horizontal component E4 and a vertical component S4. The components E3 and E4 tend to shift the roof 20 horizontally toward the East with respect to the cable 97 and with respect to the East side wall 11, thereby corresponding further to compress the East segment of the resilient sealing mechanism 30; and the components W1 and W2 tend to shift the roof 20 horizontally toward the West with respect to the cable 97 and with respect to the West side wall 11, thereby correspondingly further to compress the West segment of the resilient sealing mechanism 30. The components S1 and S4 tend to rotate the roof 20 in the counterclockwise direction about the cable 97 and further to compress the South segment of the resilient sealing mechanism 30; and the components N2 and N3 tend to rotate the roof 20 in the clockwise direction about the cable 97 and further to compress the North segment of the resilient sealing mechanism 30. Shifting of the roof 20 either East or West with respect to the cable 97 effects no particular force thereupon, since the rollers 113 incorporated in the cable guiding device 110 accommodate ready and unrestrained relative radial movements of the cable 97 with respect thereto. However, rotation of the roof 20 in either direction about the cable 97 effect corresponding forces upon the cable 97, since the rollers 113 incorporated in the cable guiding device 110 resist relative circumferential movements of the cable 97 with respect thereto, whereby the intermediate section of the cable is correspondingly deflected from its vertical position. Further, it is pointed out that a true spinning rotation of the roof 20 in either direction about its own center also produces a corresponding S or N force applied between the roof 20 and the cable 97 by the cable guiding device 110, whereby the intermediate section of the cable 97 is correspondingly deflected from its vertical position. Any further compression of any segment of the resilient sealing mechanism 30 is productive of a corresponding opposing and restoring force upon the roof 20; and any deflection of the intermediate section of the cable 97 out of its normal vertical position or attitude is productive of a corresponding opposing and restoring force upon the roof 20. Thus, both the sealing mechanism 30 and the cable 97 tend to restore the floating roof 20 back into its normal centered position with respect to the side wall 11 in the event of movement therefrom of the roof 20. In the arrangement, the cable 97 is very effective to restore the floating roof 20 back into its normal rotary centered position in the event of a true spinning rotation thereof about its own center.

Reverting to FIG. 3, it is mentioned the tube 96 is

substantially rectangular in horizontal cross section, including two relative long sides 96a extending in the radial direction and two relatively short sides 96b extending in the circumferential direction; whereby the upstanding opening extending through the tube 96 is wide or long in the radial direction and narrow or short in the circumferential direction; which arrangement accommodates relative radial movement of the cable 97 between the rollers 113 and prevents any substantial circumferential movement of the cable 97 between the rollers 113; whereby there is no drag or interference between the cable 97 and the tube 96 in the relative movements of the cable 97 with respect to the tube 96 and through the tube 96. Thus, the coaction between the cable 97 and the cable guiding device 110 not only opposes and limits movements of the floating roof 20 out of its normal rotary centered position, but also restores the floating roof 20 back into its normal rotary centered position following a movement therefrom, as explained above. Of course, the character of the above mentioned coaction may be preset by proper adjustment of the initial tension in the cable 97, when it occupies its normal vertical position; which adjustment may be readily accomplished by adjustment of the tension device 80, in the manner previously explained.

In connection with the operation of the mechanism 50, it is noted that the forces produced in the cable 97 are transferred by the beams 61 and 71 directly to the side wall 11, and independently of the bottom wall 12; which arrangement is very advantageous, since the side wall 11 is initially stiff and is further stiffened by the stored liquid in the tank 10. The exclusion of the bottom wall 12 from this connection prevents working of the bottom wall 12, the usual "oil-can" effect thereof, whereby the characteristics of the mechanism 50 may be accurately preset and maintained in the operation thereof over the total band of variable conditions encountered thereby and relating to weather, to the head of the stored liquid in the tank 10, etc. Further, it is noted in this regard, that any desired additional stiffness may be readily introduced into the side wall 11 by the simple expedient of rigidly securing to the exterior surface thereof one or more upstanding beams or columns, not shown, arranged in the vicinity of the mechanism 50. For example, a rigid column might extend from the curb 13 to the bottom wall 12 through an opening provided in the wind girder 14, such column being positioned substantially below the column 62 and arranged in upstanding position in contact with the exterior surface of the side wall 11 and suitably rigidly secured thereto.

Referring now to FIGS. 8 to 10, inclusive, a modified form of the cable guiding device 120 is there illustrated, which is considered at the present, to comprise the preferred and most advantageous form thereof. In this embodiment, the top end of the tube 96 projects upwardly somewhat above the top plate 26 of the outer pontoon 22, as indicated in FIGS. 9 and 10; and the device 120 comprises a pair of upstanding radially extending plates 121 arranged in circumferentially spaced-apart relation and respectively rigidly secured at the bottom ends thereof to the top ends of the long sides 96a of the tube 96, and a pair of upstanding circumferentially extending plates 122 arranged in radially spaced-apart relation and respectively rigidly secured at the bottom ends thereof to the top ends of the short sides 96b of the tube 96. The plates 121 project only somewhat above the top end of the tube 96 and terminate in oppositely directed flanges 123 disposed in a lower substantially horizontal plane; while the plates 122 project well above the top end of the tube 96 and terminate in oppositely directed flanges 124 disposed in an upper substantially horizontal plane. A pair of elongated spindles 125 are carried by the plates 122 in an intermediate substantially horizontal plane, the spindles 125 extending in the radial direction and being spaced-apart in

the circumferential direction. As a practical matter the spindles 125 are parallel to each other, since the radial distance between the center of the floating roof 20 and the spindles 125 is so great relative to the lengths of the spindles 125; and further the spindles 125 are arranged on opposite sides of the long sides 96a of the tube 96, as best shown in FIG. 10. The spindles 125 may be firmly secured in place upon the plates by nuts 126 carried upon threaded outer ends thereof, as best shown in FIG. 9. Two rollers 127 and 128 are respectively mounted upon the spindles 125 for both rotation thereabout and sliding movements therealong, the two rollers 127 and 128 being respectively carried by two elongated bearing sleeves 129 and 130 to improve the stability thereof. The roller 128 is in the form of a sheave pulley and comprises a central cylindrical barrel 128a and a pair of enlarged side flanges 128b; which side flanges 128b respectively embrace the sides of the roller 127; whereby the two rollers 127 and 128 are locked together for movements along the respective spindles 125. The cable 97 is arranged between the rollers 127 and 128; the outer periphery of the roller 127 and the outer periphery of the barrel 128a of the roller 128 respectively engage the opposite sides of the cable 97; and the flanges 128b trap the cable 97 in place therebetween.

In view of the foregoing, it will be understood that vertical movement of the cable 97 in either direction through the tube 96 merely effects rotation of the rollers 127 and 128 upon the spindles 125; and radial movement of the cable 97 in either direction effects corresponding sliding movements of the two rollers 127 and 128 along the respective spindles 125. On the other hand, the two rollers 127 and 128 respectively oppose circumferential movements in the respective directions with respect to the tube 96 of the cable 97, whereby the corresponding one of the rollers 127 and 128 effects deflection of the intermediate section of the cable 97 from its normal vertical position for the purpose previously explained.

The cable guiding device 120 incorporates a lower sealing device 140 for the purpose of minimizing the escape through the tube 96 of vapors from the liquid stored in the tank 10; which device 140 essentially comprises a sheet 141 formed of rubberized fabric, or the like, and arranged on top of the flanges 123 carried by the tops of the plates 121; which sheet 141 is suitably clamped in place by a pair of overlying strips 142 respectively secured to the flanges 123 by rivets 143. The sheet 141 has an elongated slit 141a therein through which the cable 97 passes; whereby the sheet 141 closely surrounds the cable 97, while the slit 141a therein accommodates the required radial movements of the cable 97 with respect to the tube 96.

The plates 122 carry a hood 145 that includes a top wall 146 and a pair of downwardly directed side walls 147, the top wall 146 being disposed above the rollers 127 and 128 and rigidly secured to the flanges 124 carried by the plates 122; which top wall 146 has an elongated radially extending slot 146a therein, so as to accommodate the required radial movements of the cable 97 with respect to the tube 96, without interference by the top wall 146 of the hood 145. The hood 145 incorporates an upper sealing device 150 for the purpose of minimizing the entry of rain and the other elements of weather into the hood 145 and thence into the rollers 127 and 128 and onto the spindles 125; which device 150 essentially comprises a sheet 151 formed of rubberized fabric, or the like, and arranged on top of the top wall 146 of the hood 145 and in covering relation with the slot 146a formed in the top wall 146; which sheet 151 is suitably clamped in place by a pair of overlying strips 152 respectively secured to the top wall of the hood 145 and to the flanges 124 by rivets 153. The sheet 151 has an elongated slit 151a therein through which the

cable 97 passes; whereby the sheet 151 closely surrounds the cable 97, while the slit 151a therein accommodates the required radial movements of the cable 97 with respect to the tube 96.

The hood 145 and the sealing device 150 cooperate to protect the rollers 127 and 128 and the spindles 125 against rain and the other elements of weather; which arrangement is very advantageous, since a freezing rain and the resulting ice could easily lock the rollers 127 and 128 to the respective spindles 125, thereby preventing both rotation and sliding of the rollers 127 and 128 upon the spindles 125, so as greatly to interfere with the normal and desired mode of operation of the cable guiding device 120, in the manner previously explained.

Referring now to FIGS. 11 and 12, another modified form of the cable guiding device 160 is there illustrated; and in this embodiment, the top end of the tube 96 projects upwardly somewhat above the top plate 26 of the outer pontoon 22; and rigidly secured to the top of the tube 96 is a cover plate 96x having an elongated radially extending slot 96y therein. The device 160 comprises a pair of radially extending and circumferentially spaced-apart upstanding rails 161 rigidly secured to the top of the cover plate 96x, the rails 161 being substantially parallel to each other, since the radial distance from the center of the floating roof 20 to the rails 161 is so great relative to the dimensions of the rails 161. The rails 161 carry at the tops thereof a pair of inwardly directed flanges 162 disposed in substantially parallel spaced-apart relation and extending in the radial direction. An annular race 163 is arranged between the adjacent edges of the flanges 162; which race 163 carries at the top and bottom ends thereof two annular washers 164 and 165 that are rigidly secured thereto. The top and bottom washers 164 and 165 are respectively positioned above and below the flanges 162; whereby the race 163 is mounted for radial sliding movements between the flanges 162. Aligned holes are centrally disposed in the washers 164 and 165; the cable 97 extends vertically through the slot 96y provided in the cover plate 96x, and through the race 163, and also through the holes provided in the washers 164 and 165. Finally, the device 160 comprises a plurality of balls 166 formed of bronze, or the like, and arranged interiorly of the race 163 and exteriorly of the adjacent section of the cable 97 and in engagement with the cable 97 and the race 163; and the spaces between the balls 166 and between the balls 166 and the race 163 may be filled with a suitable heavy grease, not shown, to insure easy rolling of the balls 166.

In view of the foregoing, it will be understood that vertical movement of the cable 97 in either direction through the tube 96 merely effects rolling of the balls 166 in the race 163; and radial movement of the cable in either direction effects corresponding sliding or rolling movements, as required, of the unit including the race 163, the balls 166 and the washers 164 and 165 along the flanges 162. On the other hand, the balls 166 oppose circumferential movements in the respective directions with respect to the tube 96 of the cable 97, whereby the balls 166 effect deflection of the intermediate section of the cable 97 from its normal vertical position for the purpose previously explained.

In the cable guiding devices 110 and 160 no lower and upper sealing devices, respectively corresponding to the sealing structure 140 and 150 incorporated in the cable guiding device 120, have been disclosed as being incorporated therein; however, it will be understood that such sealing structures could be readily incorporated into the cable guiding devices 110 and 160 in a manner following the disclosure made in conjunction with the cable guiding device 120.

In view of the foregoing it is apparent that there has been provided an anti-rotational mechanism for a floating roof arranged in a storage tank for liquids, such as petroleum products, wherein the mechanism is of im-

proved and economical construction and arrangement and is positive and simple in operation.

While there has been described what is at present considered to be the preferred embodiment of the invention, it will be understood that various modifications may be made therein, and it is intended to cover in the appended claims all such modifications as fall within the true spirit and scope of the invention.

What is claimed is:

10. 1. In a tank for storing liquids, such as petroleum products, including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof being positioned radially inwardly with respect to said side wall to provide a substantially annular space therebetween, and substantially annular sealing structure carried by the periphery of said floating roof and arranged in said annular space and disposed in sliding sealed engagement with said side wall, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding passage therethrough, a strong flexible resilient cable arranged in said tank and secured in taut condition between said upper and lower anchor structures and extending through said upstanding passage, said floating roof having a normal rotary centered position with respect to said side wall wherein said upstanding passage is disposed in a position of vertical alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts a force through said cable guiding device upon said floating roof that is productive of a torque thereupon tending to restore said floating roof back into its normal rotary centered position.
2. In a tank for storing liquids, such as petroleum products, including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof being positioned radially inwardly with respect to said side wall to provide a substantially annular space therebetween, and substantially annular sealing structure carried by the periphery of said floating roof and arranged in said annular space and disposed in sliding sealed engagement with said side wall,

whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding passage therethrough, a strong flexible resilient cable arranged in said tank and secured in taut condition between said upper and lower anchor structures and extending through said upstanding passage, said floating roof having a normal rotary centered position with respect to said side wall wherein said upstanding passage is disposed in a position of vertical alignment with said upper and lower anchor structures and said cable occupies substantially a vertical position, a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, and a sealing device carried by said floating roof and cooperating with said upstanding passage and the intermediate section of said cable in order to prevent any substantial escape of vapors from the stored liquid through said upstanding passage while accommodating ready feeding of said cable therethrough, undesirable rotation of said floating roof in either direction out of its normal rotary centered position causing said cable guiding device correspondingly to deflect the intermediate section of said cable from its substantially vertical position, whereby said thus deflected cable exerts a force through said cable guiding device upon said floating roof that is productive of a torque thereupon tending to restore said floating roof back into its normal rotary centered position.

3. In a tank for storing liquids, such as petroleum products, including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof being positioned radially inwardly with respect to said side wall to provide a substantially annular space therebetween, and substantially annular sealing structure carried by the periphery of said floating roof and arranged in said annular space and disposed in sliding sealed engagement with said side wall, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding passage therethrough, a strong flexible resilient cable arranged in said tank and secured in taut condition between said upper and lower anchor structures and extending through said upstanding passage, said floating roof having a normal rotary centered position with respect to said side wall wherein said upstanding passage is disposed

in a position of vertical alignment with said upper and lower anchor structures and said cable occupies substantially a vertical position, a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, and first and second sealing devices carried by said floating roof and respectively positioned below and above said cable guiding device, said first sealing device cooperating with said upstanding passage and the intermediate section of said cable in order to prevent any substantial escape of vapors from the stored liquid through said upstanding passage while accommodating ready feeding of said cable therethrough, said second sealing device cooperating with said cable guiding device and the intermediate section of said cable in order to prevent any substantial entry of rain and the other elements of weather into said cable guiding device while accommodating ready feeding of said cable therethrough, undesirable rotation of said floating roof in either direction out of its normal rotary centered position causing said cable guiding device correspondingly to deflect the intermediate section of said cable from its substantially vertical position, whereby said thus deflected cable exerts a force through said cable guiding device upon said floating roof that is productive of a torque thereupon tending to restore said floating roof back into its normal centered position.

4. In a tank for storing liquids, such as petroleum products, including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof including a substantially annular outer pontoon provided with an outer rim and an inner rim and a top plate connecting the top portions of said outer and inner rims and a bottom plate connecting the bottom portions of said outer and inner rims, said outer rim being positioned radially inwardly with respect to said side wall to provide a substantially annular space therebetween, and substantially annular sealing structure carried by said outer rim and arranged in said annular space and disposed in sliding sealed engagement with said side wall, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to said outer pontoon, lower anchor structure rigidly carried by said side wall adjacent to the bottom thereof and projecting generally radially inwardly into underhanging relation with respect to said outer pontoon, said upper and lower anchor structures being arranged substantially in vertical alignment with each other, an upstanding tube arranged in an outer peripheral portion of said outer pontoon and respectively sealed adjacent to the top and bottom ends thereof to said top and bottom plates so as to define an upstanding passage through said tube and consequently through the outer peripheral portion of said outer pontoon, a strong flexible resilient cable arranged in said tank and secured in taut condition between said upper and lower anchor structures and extending through the upstanding passage in said tube, said floating roof having a normal rotary centered position with respect to said side wall wherein the upstanding passage in said tube is disposed in a position of vertical alignment with said upper and lower anchor structures and said cable occupies substantially a vertical position, a pair of end plates carried by said top plate respectively adjacent to radially spaced-apart portions of the top end of said tube, a pair of elongated radially extending spindles

carried by said end plates respectively adjacent to circumferentially spaced-apart portions of the top end of said tube, a pair of guide rollers respectively mounted upon said spindles for both rotational movements thereupon and radial sliding movements therealong and respectively engaging the corresponding opposite sides of the intermediate section of said cable, one of said guide rollers carrying a pair of flanges respectively engaging the opposite sides of the other of said guide rollers so that said guide rollers are respectively slidable simultaneously along said spindles, said guide rollers accommodating ready feeding of said cable therethrough and through the upstanding opening in said tube incident to vertical movement in either direction of said floating roof with respect to said side wall, said guide rollers accommodating radial movement in either direction of said floating roof with respect to the intermediate section of said cable by corresponding sliding of said guide rollers along said spindles and without corresponding deflection of the intermediate section of said cable from its substantially vertical position, side guide rollers accommodating circumferential movement in either direction of said floating roof with respect to the intermediate section of said cable with corresponding deflection thereof from its substantially vertical position, whereby said thus deflected cable exerts a force through the corresponding one of said guide rollers upon said floating roof that is productive of a torque thereupon tending to restore said floating roof back into its normal rotary centered position, a first sealing device carried by the top end of said tube and positioned below said guide rollers, said first sealing device cooperating with the upstanding passage in said tube and the intermediate section of said cable in order to prevent any substantial escape of vapors from the stored liquid through the upstanding passage in said tube while accommodating ready feeding of said cable therethrough and ready radial movements of said floating roof with respect to the intermediate section of said cable, a hood carried by said end plates and positioned above said guide rollers and having an opening therein through which said cable extends and a second sealing device carried by said hood and cooperating with the opening therein and the intermediate section of said cable in order to prevent any substantial entry of rain and the other elements of weather into said hood while accommodating ready feeding of said cable therethrough and ready radial movements of said floating roof with respect to the intermediate section of said cable.

5. The combination set forth in claim 4, wherein each of said first and second sealing devices essentially comprises a sheet of flexible material having a radially extending slit therein through which the intermediate section of said cable extends.

6. The combination set forth in claim 4, wherein the dimension of said tube in the radial direction is substantially greater than the dimension of said tube in the circumferential direction, thereby to accommodate radial movements in either direction of said floating roof with respect to the intermediate section of said cable without substantial engagement between said tube and said cable.

7. In a tank for storing liquids, such as petroleum products, including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof being positioned radially inwardly with respect to said side wall to provide a substantially annular space therebetween, and substantially annular sealing structure of the resilient tubular-seal type carried by the periphery of said floating roof and arranged in said annular space and disposed in sliding sealed engagement with said side wall, whereby said sealing structure biases said floating roof into a normal radial centered position with respect to said side wall while accommodating rotation of said floating roof in a generally horizontal plane

with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding passage therethrough, a strong flexible resilient cable arranged in said tank and secured in taut condition between said upper and lower anchor structures and extending through said upstanding passage, said floating roof having a normal rotary centered position with respect to said side wall wherein said upstanding passage is disposed in a position of vertical alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position, whereby said thus deflected cable exerts a force through said cable guiding device upon said floating roof that is productive of a torque thereupon tending to restore said floating roof back into its normal rotary centered position.

8. In a tank for storing liquids including an upstanding substantially cylindrical side wall, a substantially disk-shaped piston-like floating roof arranged in said tank in floating relation with the stored liquid and movable in the vertical direction with respect to said side wall in accordance with the head of the stored liquid, and means for positioning said floating roof radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding passage therethrough, a strong flexible resilient cable arranged in said tank and secured in taut condition between said upper and lower anchor structures and extending through said upstanding passage, said floating roof having a normal rotary centered position with respect to said side wall wherein said upstanding passage is disposed in a position of vertical alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said up-

standing passage incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts a force through said cable guiding device upon said floating roof that is productive of a torque thereupon tending to restore said floating roof back into its normal rotary centered position.

9. The combination set forth in claim 8, wherein said cable is prestretched prior to its arrangement in taut condition between said upper and lower anchor structures and passing through said upstanding passage.

10. The combination set forth in claim 8, wherein said cable is formed essentially of stainless steel.

11. The combination set forth in claim 8, wherein said cable guiding device essentially comprises a pair of rollers respectively engaging the opposite sides of the intermediate section of said cable and mounted for rotation about a pair of substantially horizontally disposed and substantially radially directed axes.

12. The combination set forth in claim 8, wherein said cable guiding device essentially comprises an annular race surrounding the intermediate section of said cable and carrying a plurality of balls respectively engaging a corresponding plurality of circumferentially spaced-apart portions of said surrounded intermediate section of said cable.

13. The combination set forth in claim 8, wherein said cable guiding device essentially comprises a flanged sheave and a roller respectively engaging the opposite sides of the intermediate section of said cable, said roller also being positioned between the flanges of said sheave, and said sheave and said roller being mounted for rotation about two substantially horizontally disposed and substantially radially directed axes.

14. In a tank for storing liquids including an upstanding substantially cylindrical side wall, a substantially disk-shaped piston-like floating roof arranged in said tank in floating relation with the stored liquid and movable in the vertical direction with respect to said side wall in accordance with the head of the stored liquid, and means for positioning said floating roof radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding passage therethrough, a tension control device carried by said upper anchor structure, a strong flexible resilient cable arranged in said tank and secured in taut condition between said tension control device and said lower anchor structure and extending through said upstanding passage, said tension control device being selectively operable to preset the normal tension in said cable between said upper and lower anchor structures, said floating roof having a normal rotary centered position with respect to said side wall wherein said upstanding opening is disposed in a position of vertical alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts

alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts

15. In a tank for storing liquids including an upstanding substantially cylindrical side wall, a substantially disk-shaped piston-like floating roof arranged in said tank in floating relation with the stored liquid and movable in the vertical direction with respect to said side wall in accordance with the head of the stored liquid, and means for positioning said floating roof radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, and outer peripheral portion of said floating roof having an upstanding passage therethrough, a resilient mounting and tension control device carried by said upper anchor structure, a strong flexible cable arranged in said tank and secured in taut condition between said resilient mounting and tension control device and said lower anchor structure and extending through said upstanding passage, said resilient mounting and tension control device introducing resiliency in the mounting of said cable between said upper and lower anchor structures and being selectively operable to preset the normal tension in said cable between said upper and lower anchor structures, said floating roof having a normal rotary centered position with respect to said side wall wherein said upstanding passage is disposed in a position of vertical alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts

a force through said cable guiding device upon said floating roof that is productive of a torque thereupon tending to restore said floating roof back into its normal rotary centered position.

16. In a tank for storing liquids including an upstanding substantially cylindrical side wall having an open top, an annular outwardly directed curb carried by an annular outwardly directed curb carried by the top of said side wall, an annular outwardly directed wind girder carried by the upper portion of said side wall and positioned below said curb and extending radially outwardly well beyond said curb, a substantially disk-shaped piston-like floating roof arranged in said tank in floating relation with the stored liquid and movable in the vertical direction with respect to said side wall in accordance with the head of the stored liquid, and means for positioning said floating roof radially inwardly with respect to said side wall to provide a substantially annular space therebetween, whereby said floating roof is subject to rotation in a generally horizontal plane with respect to said side wall; mechanism for controlling and limiting said rotation of said floating roof comprising an upper beam arranged at the top of said tank, the intermediate portion of said upper beam being rigidly mounted on the top of said curb, the outer end of said upper beam projecting generally radially outwardly into overhanging relation with respect to said wind girder and the inner end of said upper beam projecting generally radially inwardly into overhanging relation with respect to the outer peripheral portion of said floating roof, a tie connecting the outer end of said upper beam to said wind girder, a lower beam arranged in said tank adjacent to the bottom thereof, the outer end of said lower beam being rigidly secured to said side wall adjacent to the bottom thereof and the inner end of said lower beam projecting generally radially inwardly into underhanging relation with the outer peripheral portion of said floating roof, the inner ends of said upper and lower beams being arranged substantially in vertical alignment with each other, an outer peripheral portion of said floating roof having an upstanding passage therethrough, a strong flexible resilient cable arranged in said tank and secured in taut condition between the inner ends of said upper and lower beams and extending through said upstanding passage, said floating roof having a normal rotary centered position with respect to said side wall wherein said upstanding passage is disposed in a position of vertical alignment with the inner ends of said upper and lower beams and said cable occupies substantially a vertical position, and a cable guiding device carried by said floating roof adjacent to said upstanding passage and engaging the intermediate section of said cable and accommodating ready feeding of said cable therethrough and through the upstanding passage in said tube incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts a force through said cable guiding device upon said floating roof that is productive of a torque thereupon tending to restore said floating roof back into its normal rotary centered position.

17. In a tank for storing liquids including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof including a substantially annular outer pontoon provided with an outer rim and an inner rim and

a top plate connecting the top portions of said outer and inner rims and a bottom plate connecting the bottom portions of said outer and inner rims, and means for positioning said outer rim radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to said outer pontoon, lower anchor structure rigidly carried by said side wall adjacent to the bottom thereof and projecting generally radially inwardly into underhanging relation with respect to said outer pontoon, said upper and lower anchor structures being arranged substantially in vertical alignment with each other, an upstanding tube arranged in an outer peripheral portion of said outer pontoon and respectively sealed adjacent to the top and bottom ends thereof to said top and bottom plates so as to define an upstanding passage through said tube and consequently through the outer peripheral portion of said outer pontoon, a strong flexible resilient cable arranged in said tank and secured in taut condition between said upper and lower anchor structures and extending through the upstanding passage in said tube, said floating roof having a normal rotary centered position with respect to said side wall wherein the upstanding passage in said tube is disposed in a position of vertical alignment with said upper and lower anchor structures and said cable occupies substantially a vertical position, and a cable guiding device carried by said top plate adjacent to said tube and engaging the intermediate section of said cable and accommodating ready feeding of said cable therethrough and through the upstanding passage in said tube incident to vertical movement in either direction of said floating roof with respect to said side wall, said cable guiding device also being operative to accommodate radial movement in either direction of said floating roof with respect to the intermediate section of said cable without corresponding deflection thereof from its substantially vertical position and to accommodate circumferential movement in either direction of said floating roof with respect to the intermediate section of said cable with corresponding deflection thereof from its substantially vertical position, whereby said thus deflected cable exerts a force through said cable guiding device upon said floating roof that is productive of a torque thereupon tending to restore said floating roof back into its normal rotary centered position.

18. In a tank for storing liquids including an upstanding substantially cylindrical side wall, a substantially disk-shaped piston-like floating roof arranged in said tank in floating relation with the stored liquid and movable in the vertical direction with respect to said side wall in accordance with the head of the stored liquid, and means for positioning said floating roof radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to the outer peripheral portion of said floating roof, lower anchor structure rigidly carried by said side wall adjacent to the bottom thereof and projecting generally radially inwardly into underhanging relation with respect to the outer peripheral portion of said floating roof, said upper and lower anchor structures being arranged substantially in vertical alignment with each other, an outer peripheral portion of said floating roof having an upstanding slot-like passage therethrough and orientated substantially in the radial direction, whereby said upstanding passage is

relatively narrow in the circumferential direction and is relatively long in the radial direction, a strong flexible resilient cable arranged in said tank and secured in taut condition between said upper and lower anchor structures and extending through said upstanding passage, said floating roof having a normal rotary centered position with respect to said side wall wherein said upstanding passage is disposed in a position of vertical alignment with said upper and lower anchor structures and said cable occupies substantially a vertical position, and a cable guiding device carried by said floating roof adjacent to said upstanding passage and engaging the intermediate section of said cable and accommodating ready feeding of said cable therethrough and through said upstanding passage incident to vertical movement in either direction of said floating roof with respect to said side wall, said cable guiding device being operative to accommodate substantially unrestrained relative radial movements between said floating roof and the intermediate section of said cable and to accommodate no substantial relative circumferential movements between said floating roof and the intermediate section of said cable, whereby undesirable rotation of said floating roof in either direction out of its normal rotary centered position causes said cable guiding device correspondingly to resolve such rotation into corresponding radial and circumferential motion components with the result that only the circumferential motion component of said floating roof is applied to the intermediate section of said cable to deflect the same from its normal substantially vertical position, so that said thus deflected cable exerts a corresponding circumferentially applied force through said cable guiding device upon said floating roof that is productive of a torque thereupon tending to restore said floating roof back into its normal rotary centered position.

19. In a tank for storing liquids including an upstanding substantially cylindrical side wall, a substantially disk-shaped piston-like floating roof arranged in said tank in floating relation wth the stored liquid and movable in the vertical direction with respect to said side wall in accordance with the head of the stored liquid, said floating roof including a substantially annular outer pontoon provided with an outer rim and an inner rim and a top plate connecting the top portions of said outer and inner rims and a bottom plate connecting the bottom portions of said outer and inner rims, and means for positioning said outer rim radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to said outer pontoon, lower anchor structure rigidly carried by said side wall adjacent to the bottom thereof and projecting generally radially inwardly into underhanging relation with respect to said outer pontoon, said upper and lower anchor structures being arranged substantially in vertical alignment with each other, an upstanding tube arranged in an outer peripheral portion of said outer pontoon and respectively sealed adjacent to the top and bottom ends thereof to said top and bottom plates so as to define an upstanding passage through said tube and consequently through the outer peripheral portion of said outer pontoon, a strong flexible resilient cable arranged in said tank and secured in taut condition between said upper and lower anchor structures and extending through the upstanding passage in said tube, said floating roof having a normal rotary centered position with respect to said side wall wherein the upstanding passage in said tube is disposed in a position of vertical alignment with said upper and lower anchor structures and said cable occupies substantially a vertical position, a pair of elongated spindles

carried by said top plate and extending in the radial direction and disposed on opposite sides of the upstanding passage in said tube, and a pair of elongated guide rollers respectively rotatably mounted upon said spindles and respectively engaging the corresponding opposite sides of the intermediate section of said cable, said guide rollers accommodating ready feeding of said cable therethrough and through the upstanding opening in said tube incident to vertical movement in either direction of said floating roof with respect to said side wall and accommodating radial movement in either direction of said floating roof with respect to the intermediate section of said cable without corresponding deflection thereof from its substantially vertical position and accommodating circumferential movement in either direction of said floating roof with respect to the intermediate section of said cable with corresponding deflection thereof from its substantially vertical position, whereby said deflected cable exerts a force through the corresponding one of said guide rollers upon said floating roof that is productive of a torque thereupon tending to restore said floating roof back into its normal rotary centered position.

20. In a tank for storing liquids including an upstanding substantially cylindrical side wall, a substantially disk-shaped piston-like floating roof arranged in said tank in floating relation with the stored liquid and movable in the vertical direction with respect to said side wall in accordance with the head of the stored liquid, said floating roof including a substantially annular outer pontoon provided with an outer rim and an inner rim and a top plate connecting the top portions of said outer and inner rims and a bottom plate connecting the bottom portions of said outer and inner rims, and means for positioning said outer rim radially inwardly with respect to said side wall to provide a substantially annular space therebetween, whereby said floating roof is subject to rotation in a generally horizontal plane with respect to said side wall; mechanism for controlling and limiting said rotation of said floating roof comprising upper anchor structure rigidly carried by said side wall adjacent to the top thereof and projecting generally radially inwardly into overhanging relation with respect to said outer pontoon, lower anchor structure rigidly carried by said side wall adjacent to the bottom thereof and projecting generally radially inwardly into underhanging relation with respect to said outer pontoon, said upper and lower anchor structures being arranged substantially in vertical alignment with each other, an upstanding tube arranged in an outer peripheral portion of said outer pontoon and respectively sealed adjacent to the top and bottom ends thereof to said top and bottom plates so as to define an upstanding passage through said tube and consequently through the outer peripheral portion of said outer pontoon, a strong flexible resilient cable arranged in said tank and secured in taut condition between said upper and lower anchor structures and extending through the upstanding passage in said tube, said floating roof having a normal rotary centered position with respect to said side wall wherein the upstanding passage in said tube is disposed in a position of vertical alignment with said upper and lower anchor structures and said cable occupies substantially a vertical position, a pair of elongated spindles carried by said top plate and extending in the radial direction and disposed on opposite sides of the upstanding passage in said tube, and a pair of guide rollers respectively mounted upon said spindles for both rotational movements thereupon and radial sliding movements therealong and respectively engaging the corresponding opposite sides of the intermediate section of said cable, one of said guide rollers carrying a pair of flanges respectively engaging the opposite sides of the other of said guide rollers so that said guide rollers are respectively slidable simultaneously along said spindles, said guide rollers accommodating ready feeding of said cable therethrough and through the upstanding passage in said tube incident to vertical movement in

either direction of said floating roof with respect to said side wall, said guide rollers also accommodating radial movement in either direction of said floating roof with respect to the intermediate section of said cable by corresponding sliding of said guide rollers along said spindles and without corresponding deflection of the intermediate section of said cable from its substantially vertical position, side guide rollers further accommodating circumferential movement in either direction of said floating roof with respect to the intermediate section of said cable with corresponding deflection thereof from its substantially vertical position, whereby said thus deflected cable exerts a force through the corresponding one of said guide rollers upon said floating roof that is productive of a
